BUNK CRIB

William A. Van Riper, 3149-G E. Euclid Ave.,
Lynwood, Calif. 90262

Filed Dec. 19, 1966, Ser. No. 5,108

Term of patent 14 years

(Cl. D5—5)

FIG.1

FIG.4

FIG.5

FIG.2

FIG.6

FIG.3

FIG. 1 is a perspective view of a bunk crib showing my new design;

FIG. 2 is a perspective view thereof illustrating the central rail portion pivoted upwardly;

FIG. 3 is a perspective view thereof illustrating the door in the central rail portion in its open position;

FIG. 4 is a right end elevational view thereof, the left end elevational view being a mirror image;

FIG. 5 is a rear elevational view thereof; and

FIG. 6 is a top plan view thereof.

I claim:

The ornamental design for a bunk crib, substantially as shown and described.
